US00D551632S

(12) **United States Design Patent** (10) **Patent No.:** **US D551,632 S**
Kim (45) **Date of Patent:** **** Sep. 25, 2007**

(54) **WIRELESS REMOTE CONTROLLER FOR COMPUTER**

(75) Inventor: **Eui-Seek Kim**, Seoul (KR)

(73) Assignee: **Samsung Electronics Co., Ltd.**, Kyunggi-do (KR)

(**) Term: **14 Years**

(21) Appl. No.: **29/258,728**

(22) Filed: **Apr. 26, 2006**

(51) **LOC (8) Cl.** **13-03**

(52) **U.S. Cl.** **D13/168**

(58) **Field of Classification Search** **D13/168; D10/104, 106; D14/218, 247; 340/825.22, 340/825.24, 825.25, 825.31, 825.36, 825.69, 340/825.72; 341/20, 23, 34, 176; 345/156, 345/169; 348/734; 455/92, 95, 100, 128, 455/151.1–151.4, 325–355; 463/39, 42; 700/17, 19, 20, 65, 83, 275**

See application file for complete search history.

(57) **CLAIM**

The ornamental design for a wireless remote controller for computer, as shown and described.

DESCRIPTION

FIG. 1 is a top front perspective view of a wireless remote controller for computer showing our new design;

FIG. 2 is a front elevational view thereof;

FIG. 3 is a rear elevational view thereof;

FIG. 4 is a left side elevational view, the right side being symmetrical thereof; and,

FIG. 5 is a top plan view, the bottom plan being symmetrical thereof.
